TEST-BLOCK FOR ELECTRIC METERS

Ernest G. Johansson, Watertown, Mass., assignor
to The Palmer Electric & Manufacturing Co.,
Waltham, Mass., a corporation of Massachusetts

Application March 30, 1933, Serial No. 663,523

16 Claims. (Cl. 175—183)

This invention relates to a test-block adapted to facilitate the testing of an electric meter by bypassing the load current usually flowing through the meter and attaching a test load to the meter in such a way as to test the accuracy thereof. A test-block of this type is described and illustrated in the patent to Palmer No. 993,099 granted May 23, 1911.

The present invention relates to improved features of structure whereby a test-block capable of use with heavy currents can be constructed in compact and efficient form, and can be employed without the use of tools.

According to the invention the block consists of a base of insulating material on which are mounted a suitable number of pairs of housing contact elements, each element being preferably of bar stock bent to shape to receive a plug between it and its opposing element, the bends being such as to cause the contact portions of opposing elements to move closer to each other when heated, thus making a better interfacial connection with a plug between them. In each pair of contact elements, the contact portion of at least one is formed to a non-flat shape, the plug having a corresponding shape to fit, so that the plug is held in an upright position when inserted between opposing elements.

An object of the invention is to provide a test-block of which the structure is as compact as possible, consistent with the standard requirements of spacing between members of different polarity. As the spacing rules apply to movable as well as to fixed members, the movable members are constructed and arranged so as to avoid any position of operation in which they would be nearer to a member of different polarity than the minimum prescribed distance.

If a plug is pulled when it is carrying a load current, arcing occurs, especially when a heavy current is being carried. To minimize such arcing, I may provide a barrier or insulating wall between the elements of each pair, such wall being preferably secured to the insulating base. This prevents the jumping of an arc from one element to the other when a plug is pulled. Any suitable insulating material such as vulcanized fiber or the like may be used for the wall. Forked plugs are provided to straddle the wall, the legs of the plugs engaging the opposing elements of a pair so as to connect them electrically. In addition to the wall or barrier between elements of each pair, I also provide adequate insulating barriers between contact elements of different voltages. Thus the block can be compactly constructed so

as to be enclosed in a box of comparatively small size.

For a more complete disclosure of the invention, reference may be had to the description thereof which follows and to the drawing of which

Figure 1 is a plan view of a box containing an electric meter and a test-block embodying the invention.

Figure 2 is a section on line 2—2 of Figure 1.

Figure 3 is a section on line 3—3 of Figure 1.

Figure 4 is a perspective view of a pair of contact elements, a fragment of the barrier between them, and a plug adapted to connect them.

Figure 5 is a sectional view of a pair of contact elements, the barrier between them, and a plug connecting them.

Figure 6 is a section on line 6—6 of Figure 5.

Figure 7 is a similar section showing elements of different shape.

As indicated in Figure 1, the invention may be embodied in a block 10 mounted in a box 11 which is illustrated without the usual cover. A meter 12 is also mounted in the box, near the block 10 so as to be conveniently connected thereto by suitable conductors 15, 16, 17 and 18. As shown, the block 10 is provided with ten contact elements designated as 20, 21, 22, 23, 24, 25, 26, 27, 28 and 29. These elements are arranged in pairs, the elements of each pair being connectible by a suitable bridge conductor. The elements are all mounted on a base 30 of insulating material, which as indicated in Figure 2, may have an upper surface of stepped formation consisting of a lower step 35 and an upper step 36. The odd numbered contact elements are mounted on the lower step 35, the four even numbered elements which have connections leading to the meter being mounted on the upper step. The odd numbered elements on the lower step may each comprise a strip of flat bar stock having a flat mounting portion 37 secured to the base 30 and a contacting portion 38 angularly disposed with respect to the mounting portion 37 so as to extend upwardly from the mounting portion and preferably at right angles thereto. Each mounting portion 37 is clamped tightly by a suitable bolt 39 or otherwise, to a connecting lug 42. As shown in Figure 2, the free end portions 43 of these lugs are bent downwardly along the face 44 of the step 35 to prevent turning of the lugs on their bolts. Thus the projecting portions 42 of lugs of different polarity are prevented from moving nearer to each other than the prescribed minimum spacing distance. The even numbered contact ele-

ments are likewise preferably made of flat bar stock and are shaped as to have a flat mounting portion 48 and a contacting portion 41 angularly disposed relatively thereto, this contacting portion being bent so as to extend downwardly from the upper step 36 toward the lower step 35. The two contacting portions 38 and 41 of the opposing elements of each pair are preferably parallel to each other. One or both of these elements is furthermore so shaped as to present a non-flat contacting face toward the other element of the pair. As shown in Figure 6, the contacting portions of the opposing elements may have arcuate cross sections which may be disposed approximately in a common circle. The cross sections of these elements may have other shapes such as that illustrated in Figure 7. As a result of such structure the connecting plugs are held in an upright position when inserted between the elements of a pair and are prevented from inclining toward each other in such a manner as to reduce the spacing between charged parts of different polarity below the required minimum. Between the elements of each pair is fixed 25 a wall 45 of insulating material such as vulcanized fiber.

Suitable plugs are provided for connecting the elements of the several pairs. As illustrated in Figure 4, a plug may consist of a cylindrical 30 copper rod slotted as at 48 to form a pair of parallel legs 49 adapted to straddle the barrier or wall 45. The convex outer surfaces of the legs 49 are adapted to fit the concaved contact surfaces of the elements 38 and 41, as indicated in Figure 6, so as to obtain a large interfacial contact for efficient conduction of current through the connection. Each plug may be provided with an insulating handle member 50 secured to the conducting portion so that the plug may be safely 40 manipulated. If desired the plug may be constructed, as indicated in Figure 5, by bending a piece of flat bar stock into U-shape, the legs 51 of the U-shaped member being suitably shaped so as to fit against the opposing faces of the contacting portions 38 and 41 of the elements of a pair. An anchoring pin 52 may be employed to secure the conducting member in the handle 50. Since 45 a bent strip of metal tends to straighten out when heated, it is evident that each of the contacting portions of opposing contact elements will, when heated, tend to move toward the contacting portion of the opposing element. The plug itself also will tend to expand when heated, so that it is evident that a rise of temperature of parts will 50 serve to increase the interfacial pressure between contacting elements and thereby to increase the efficiency of the electrical connection.

The various contact elements may be connected as shown in Figure 1. For example, the elements 60 23 and 25 may be connected respectively to high and low voltage line wires 60 and 61. The elements 27 and 29 may be connected respectively to low and high voltage load wires 62 and 63. The ground or intermediate voltage wire is shown 65 at 64. Ordinarily plugs are employed to connect the line wires 60 and 61 to the meter by connecting contact element 22 with element 23, and element 24 with element 25. The load wires 62 and 63 are ordinarily connected to the meter by 70 plugs connecting element 26 to 27 and element 28 to 29. The high voltage elements 22 and 23 are separated from the low voltage elements 24 and 25 as by a substantial barrier 10 extending across the upper surface of the block. This element 75 may be indented at its ends as at 11 to pro-

vide required minimum surface distance on the insulation between the nearest exposed points of high and low voltage elements. In like manner a similar fixed barrier 15 is provided between the low voltage elements 26 and 27 and the high voltage elements 28 and 29. These fixed barriers make possible the construction of a test-block occupying a relatively small space but capable of handling currents of comparatively high amperage at the customary voltage.

The contact element 21 is permanently connected to the contact element 23. Likewise the element 20 is connected as by a conductor 76 to the element 29. Thus, by inserting a plug to connect the elements 20 and 21, the high voltage line wire 60 may be by-passed around the meter to the high voltage load wire 63. The elements 25 and 27 are provided with opposing contact portions separated by a barrier 80 of suitable insulating material. If a plug be inserted to connect these elements, the low voltage line wire 61 is thus by-passed around the meter to the low voltage load wire 62. The four plugs ordinarily employed in the test-block can then be removed without disturbing the load current. A test load 25 may then be connected to the elements 26 and 28. An observation of the reading of the meter may then indicate whether the meter is indicating correctly for the particular test load employed. After the completion of the test, the four customary plugs may be reinserted in the block, thus connecting the load to the line again through the meter. The plugs between the elements 20 and 21 and between the elements 25 and 27 may then be removed so that the full load 30 current thereupon passes through the meter.

The block 10 may be elevated above the bottom of the box 11 as by a bridge 85 to which the block may be secured as by a pair of screws 86 extending through the base, insulating plugs 87 40 being placed over the heads of the screws to prevent short-circuiting.

It is evident that many modifications and changes can be made in the structure herein described without departing from the spirit or 45 scope of the invention as defined in the following claims.

I claim:

1. A test-block for a meter, comprising an insulating base having a stepped upper surface, 50 and pairs of contact elements on said base, one element of each pair having a mounting portion secured to the higher step and a contact portion bent downwardly from the mounting portion, the opposing elements of each said pair having a mounting portion on the lower step and a contacting portion bent upwardly from the mounting portion to be substantially parallel to the contact portion of the other element of the pair.

2. A test-block for a meter, comprising an insulating base having a stepped upper surface, pairs of contact elements on said base, one element of each pair having a mounting portion secured to the higher step and a contact portion 65 bent downwardly from the mounting portion, the opposing elements of each said pair having a mounting portion on the lower step and a contacting portion bent upwardly from the mounting portion to be substantially parallel to the contact portion of the other element of the pair, an insulating wall between the elements of each pair, and a U-shaped conductor adapted to straddle said wall and engage the elements of a pair.

3. A test-block for a meter, comprising an in- 75

5 sulating base, opposing contact elements arranged in pairs on said base, certain of said elements having means freely accessible for the attachment of meter-testing devices, an insulating wall fixed between the opposing elements of each pair, and a U-shaped conductor adapted to straddle said wall and engage and electrically connect the elements of a pair.

10 4. A test-block for a meter, comprising an insulating base, opposing contact elements arranged in pairs on said base, at least one of each pair of said elements presenting a non-plane contact face to the opposing element of the pair, a wall of insulating material fixed between the elements of each said pair, and a U-shaped conductor adapted to straddle said wall and fit snugly against the elements of a pair.

15 5. A test-block for a meter, comprising an insulating base, opposing contact elements arranged in pairs on said base, certain of said elements having means freely accessible for the attachment of meter-testing devices, each said element having a mounting portion secured to the base and a contact portion angularly disposed with respect thereto, an insulating wall fixed between the elements of each pair, and forked conducting plugs each adapted to straddle said wall and engage the elements of a pair.

20 6. A test-block for a meter, comprising an insulating base, opposing contact elements arranged in pairs on said base, each said element having a mounting portion secured to said base and a contact portion disposed at an angle to its mounting portion, at least one of said contact portions of each pair of elements presenting a non-flat contact face toward the other element of the pair, a wall of insulating material fixed between the elements of each pair, and a forked conducting plug adapted to straddle said wall 25 and to fit against the opposing contact faces of a pair of said elements.

25 7. A test-block for a meter, comprising an insulating base having a stepped upper surface with an upper step and a lower step, opposing contact elements arranged in pairs, one element of each pair having a flat mounting portion secured to the upper step of said base and a contact portion extending downwardly from the mounting portion, the opposite element of each pair having a mounting portion secured to the lower step of said base and a contact portion extending upwardly from the mounting portion so as to be substantially parallel to the contact portion of the other element, an insulating wall 30 fixed between the contact portions of each pair of elements, and forked conducting plugs each adapted to straddle said wall and engage the contact elements of a pair.

35 8. A test-block for a meter, comprising an insulating base, opposing contact elements arranged in pairs on said base, each said element having a flat mounting portion secured to said base and a contact portion at right angles to the mounting portion, a wall of insulating material between the elements of each pair, and connecting plugs for said pairs of elements, each said plug having a pair of spaced legs adapted to straddle the wall and engage the elements of a pair, said legs having convex cylindrical outer faces, said elements having concave faces adapted for fitted engagement with said legs.

40 9. A test-block for a meter, comprising a base of insulating material, opposing contact elements arranged in pairs, each said element being formed of flat bar stock bent to provide a flat mounting

portion secured to the base and a contact portion angularly disposed with respect to the mounting portion, said contact portion being shaped so as to present a concave face toward the opposite element of the pair, a wall of insulating material between the elements of each pair, and forked conducting plugs each adapted to straddle said wall and engage with the elements of a pair, each said plug having a pair of legs with convex outer surfaces adapted to fit the opposed concave surfaces of the contact elements.

45 10. A test-block for a meter, comprising an insulating base, pairs of contact elements mounted side by side on said base, each pair of elements having opposed contact portions arranged to form a hollow area with lateral gaps, and a barrier plate of vulcanized fiber fixed on said base and extending through said gaps to separate an element of each pair from its opposite element.

50 11. A test-block for a meter, comprising a base of insulating material, one or more pairs of separately disposed electrical conducting members mounted thereon, each of the several members consisting of a strip of metal bent and formed to provide a mounting portion attached to said base and having angularly disposed thereto a formed portion, a pair of said formed portions substantially but not completely enclosing a hollow area, a barrier of insulating material bisecting said area and closely adjacent to the side edges of said formed portions of the conducting members, and a removable U-shaped conductor straddling said barrier and filling said area to effect electrical connection between said members.

55 12. A test-block for a meter, comprising an insulating base, a barrier wall of insulating material mounted on said base, a pair of electrical conducting members mounted respectively on opposite sides of said wall, each said member consisting of a mounting portion secured to said base and a formed portion angularly disposed to said mounting portion, each said formed portion being spaced from said wall except for its side edges which substantially abut the wall, whereby each said formed portion encloses with the wall a hollow area, and a U-shaped conductor adapted to straddle said wall and to fill the pair of hollow areas enclosed by a pair of opposed conducting members so as to provide electrical connection between said members.

60 13. A test-block for a meter, comprising a plurality of pairs of contact elements, certain of said elements having means freely accessible for the attachment of meter-testing devices, and insulating means separating said elements and shielding each element from its complementary element and from all elements of polarity different therefrom on said block.

65 14. A test-block for a meter, comprising a plurality of pairs of contact elements, certain of said elements having means freely accessible for the attachment of meter-testing devices, barrier walls of insulation separating and shielding each element from its complementary element and from all elements of polarity different therefrom on said block, and individual plugs each adapted to straddle a barrier wall and electrically connect the complementary elements of a pair.

70 15. A test-block for a meter, comprising a series of pairs of contact elements arranged side by side, certain of said elements having means freely accessible for the attachment of meter-testing devices, a barrier wall of insulation extending between the elements of each of said pairs of elements, insulating walls transverse with re-

spect to said barrier wall between pairs of contact elements of different polarities, and individual plugs adapted to straddle said barrier wall and connect the complementary elements of a pair.

5. 16. A test-block for a meter, comprising a plurality of pairs of contact elements, certain of said elements having means freely accessible for the attachment of meter-testing devices, insulating means shielding each said element from its com-

plementary element and from all elements of polarity different therefrom on said block, forked connector plugs each adapted to straddle said shielding means and connect the complementary elements of a pair, said elements and plugs including means for maintaining each plug aligned with the elements connected thereby.
